POLE SPLICE

Charles Adin Fox, St. Louis, Mo., assignor to
 James R. Kearney Corporation, St. Louis, Mo.,
 a corporation of Missouri

Application August 7, 1935, Serial No. 35,085

2 Claims. (Cl. 287—125)

This invention relates generally to pole splices adapted for use particularly, though not exclusively, in connecting together pole sections for producing elongated insulated poles employed in the installation and maintenance of overhead and other electrical equipment, the predominant object of the invention being to provide an improved splice which will connect pole sections in such manner that torsional strains may be applied to the pole in either direction without loosening the splice, and which will withstand strains applied thereto either in tension or compression without affecting the joint produced by the splice.

15 Fig. 1 is a fragmentary elevation illustrating the improved splice connecting together a pair of pole sections, a small portion of the splice being broken away to show a part thereof in section.

Fig. 2 is a vertical section of the structure illustrated in Fig. 1, the fragments of pole sections being shown in elevation.

Fig. 3 is a cross-section taken on line 3—3 of Fig. 1.

Fig. 4 is a cross-section taken on line 4—4 of Fig. 2.

In the drawing, wherein is shown for the purpose of illustration, merely, one embodiment of the invention, A and B designate pole sections, and S designates generally the improved splice. The pole sections A and B are formed of suitable wood treated in a manner to provide said pole sections with the maximum electrical insulating properties. It is to be understood that an insulated pole produced through the use of the improved splice is provided with the usual attachments common to poles of this description, but as these attachments form no part of the present invention they have not been shown in the drawing.

40 The improved splice S comprises a member 1 fixed to the pole section A and a member 2 fixed to the pole section B. The member 1 is of tubular formation and receives an end portion of the pole section A, said member 1 and pole section A being secured together by means of pins 3 which are extended in opposite directions through apertures formed through the wall of the member and through the pole section. The tubular member 1 includes a transverse wall 4 which is located in spaced relation with respect to the end face A' of the pole section A which is located within said member 1, and an opening 5 which is preferably non-circular in shape is formed through said transverse wall. Extended 45 through the opening 5 formed through the trans-

verse wall 4 is a bolt 6, said bolt being provided with a head portion 6^a which is interposed between the transverse wall 4 and the adjacent end face A' of the pole section A. Also, the shank of the bolt 6 includes a non-circular portion 6^b which is disposed in the non-circular opening 5 formed through the transverse wall 4, and a screw-threaded portion 6^c. Formed on the under face of the transverse wall 4 in circular formation about the non-circular opening 10 5 therein is a plurality of radially disposed ratchet teeth 7, and formed at the lower edge of the member 1 is a beveled face 8.

The member 2 is likewise of tubular formation, and said member is secured to the pole section B by extending an end portion of said pole section into said member and passing pins 9 in opposite directions through openings formed through the wall of said member and through said pole section. At its upper end the member 2 is provided with a transverse wall portion 10, a part of said transverse wall portion being of reduced diameter as shown in Fig. 2, and an annular beveled face 11 being extended from the base of said reduced portion of the transverse wall portion 20 to the outer face of the member 2. The transverse wall portion 10 is provided with a centrally located screw-threaded opening 12, which is adapted to receive the screw-threaded shank portion of the bolt 6, said screw-threaded opening being provided with an outer, flared centering portion 13 to facilitate entrance of the end 25 of the shank of the bolt into said screw-threaded opening.

The member 2 has formed within same integrally with the side wall and the transverse wall portion thereof an extension 14 (Figs. 2 and 4) in which an opening 15 is formed, said opening 15 being formed longitudinally of said extension and being extended also through the transverse 35 wall portion 10. The opening 15 receives an elongated pawl 16 which at its lower end is recessed, as shown at 17. A coil spring 18 is extended into the recess 17 of the pawl 16, said coil spring contacting at one of its ends with the 40 face at the base of the recess 17 and at its opposite end with the face at the lower end of the opening 15, whereby the pawl is urged upwardly by said coil spring. At its upper end the pawl 45 is shaped to engage the ratchet teeth 7 formed at the lower face of the transverse wall 4 of the member 1. The side wall of the member 2 has formed therein a vertically elongated aperture 19 through which the shank portion of a pawl 50 operating element 19 is extended, said shank por- 55

tion of said element 19 having a screw-threaded inner end portion which is screwed into a screw-threaded opening formed in the pawl, and said pawl-operating element including a head portion 20 at the outer end of the shank portion thereof which is located adjacent to the outer face of the member 2.

When a pair of pole sections are to be connected together with the aid of the improved splice, said 10 pole sections are brought into alinement so that the screw-threaded shank portion of the bolt 6 may be introduced into the screw-threaded opening 12 of the transverse wall portion 10 of the member 2. The pole sections are then subjected 15 to relative rotary movement to cause the screw-threaded shank portion of the bolt 6 to be screwed through the opening 12 and thereby cause the beveled faces 8 and 11 on the members 1 and 2 to approach each other and finally seat one 20 against the other. During such relative rotary movement of the pole sections the nose portion of the pawl 16 slides idly over the ratchet teeth 7. When the pole sections have been completely 25 screwed together, the bevel faces 8 and 11 are in very close contact with each other, whereby a firm, rigid joint between the pole sections is provided which is capable of withstanding maximum compressive and tensional strains to which poles of this description are subjected. Also because 30 of the engagement between the pawl 16 and the ratchet teeth 7, torsional strains to which the pole is subjected in the unscrewing direction will not loosen the joint provided by the splice. When it is desired to dis-assemble a pair of pole sections 35 connected by the improved splice it is necessary, merely, that the head portion 20 of the pawl-operating element 19 be moved in a direction to disengage the pawl from the ratchet teeth, whereupon the pole sections may be unscrewed without 40 interference from the pawl.

An important feature of the invention is that the threads on the bolt 6 are protected from damage due to the fact that the screw-threaded portion of the shank of said bolt is largely located 45 within the tubular structure of the member 1. Thus rough handling of the pole sections will not cause such burring of the screw-threads of the bolt 6 as to cause inconvenience in assembling and dis-assembling the pole sections.

I claim:

1. A splice for connecting a pair of pole sections comprising a pair of members fixed to said pole sections, a screwthreaded element carried by one of said members, said screwthreaded element being provided with an enlarged head portion which is confined between a part of the member with which said screwthreaded element is associated and an end face of the associated pole section whereby longitudinal movement of said screwthreaded element is prevented, means for preventing rotary movement of said screwthreaded element with respect to the member with which said screwthreaded element is associated, said screwthreaded element being screwthreadedly received by a screwthreaded opening formed in the other of said members so as to connect said pair of members and the associated pole sections together, and releasable means carried by one of said members and engageable with the other of said members to prevent unintended relative rotary movement of said members in the unscrewing direction. 5

2. A splice for connecting a pair of pole sections comprising a pair of members fixed to said pole sections, a screwthreaded element carried by one of said members, said screwthreaded element being provided with an enlarged head portion, which is confined between a part of the member with which said screwthreaded element is associated and an end face of the associated pole section whereby longitudinal movement of said screwthreaded element is prevented, said screwthreaded element having a noncircular portion which is disposed in a noncircular opening 10 formed in the member that carries said screwthreaded element so as to prevent relative rotary movement between said screwthreaded element and said member, said screwthreaded element being screwthreadedly received by a screwthreaded opening formed in the other of said members so as to connect said pair of members and the associated pole sections together, and releasable means carried by one of said members and engageable with the other of said members to prevent unintended relative rotary movement 15 of said members in the unscrewing direction. 20

CHARLES ADIN FOX.
